3,316,568 HOSPITAL MATTRESS WITH ARTICULATED FRAME

Melvin N. Janapoli, 6000 Avalon Blvd.,
Los Angeles, Calif. 90003
Filed Apr. 29, 1966, Ser. No. 546,237
6 Claims. (Cl. 5—351)

This application is a continuation-in-part of application Ser. No. 340,089, filed Jan. 24, 1964, entitled, "Articulated Hospital Bedding," now Patent No. 3,249,952.

This invention relates to bedding and is particularly concerned with mattresses or the like which must be articulate in order to comfortably position a person lying thereon, it being a general object of this invention to provide bedding of this character which articulates freely while maintaining uniform cushioning effect.

Articulated mattresses are commonly employed in hospitals and like establishments, being supported on adjustable beds that comprise selectively movable frame sections. The adjustable bed is not part of the present invention, but is the underlying support upon which the bedding of the present invention must freely articulate. In practice, adjustable beds have two or more relatively movable sections; and most often have three sections, a head section, a center section and a foot section. Ordinarily, these sections are simply pivotally joined one to the other (in relation as indicated in FIG. 1) and the pivotal points of joinder are independently elevated by suitable means (not shown).

Bedding heretofore provided for use on adjustable beds of the type hereinabove referred to has been a subject of concern in institutions such as hospitals where patients are bedridden for long periods of time. In addition to the comfort of the patient hygiene must be considered and ordinary bedding is not altogether conducive to either, since no provision is made therein to properly control articulation and simultaneously maintain uniform cushioning effect. More particularly, ordinary bedding or mattresses of this type are merely sectional, with sufficient space between the springs or sections to permit the cover or padding to bend. It is true that padding is ordinarily provided to span between the sections, but continued and uncontrolled bending soon results in deterioration of the bedding at the points of joinder. As a result, such bedding does not provide a neat and predetermined bend line, but on the contrary is redundant with random folds and undesirable creases accompanied by rapid breaking up of the padding structure.

An object of this invention is to provide an articulated mattress, wherein sections thereof which are movable relative to each other are hinged on axes in such a manner that the cushioning and/or padding remains uniformly effective throughout the length of the mattress.

Another object of this invention is to provide an articulated mattress, wherein each section comprises a framework integrated with springs and adapted to be hingedly joined together by pivots without adverse effect on the cushioning and/or padding.

The various objects and features of my invention will be fully understood from the following detailed description of the typical preferred form and application of my invention, throughout which description reference is made to the accompanying drawings, in which:

FIG. 1 is a perspective view of a unit of bedding shown in a typical disposition.

FIG. 2 is a perspective view of the frame sections involved, the multiplicity of spring coils being removed.

FIGS. 3 and 4 are detailed sectional views taken as indicated by lines 3—3 and 4—4 on FIG. 1.

FIGS. 5 through 7a are top and bottom views of the

2

three frame sections involved in the preferred form of the invention as indicated at each figure of the drawings.

The mattress herein disclosed is a self-contained unit having characteristics of an inner-spring mattress. However, special provision is made for articulation at one or more transverse points, and since the invention is primarily concerned with hospital beds and the like, it is the standardized bed of this type to which I will hereinafter describe my mattress as being applied. The hospital bed which is most often employed involves a plurality of three supporting sections, the head section, the center section and the foot section. Therefore, I will now describe the preferred form of my invention as it is applicable to such a hospital bed and wherein my mattress also has corresponding sections, there being a head section A, a center section B, and a foot section C. In addition to the three general sections A, B and C, there is a top padding D, a bottom padding E, and a cover F. As is clearly shown in FIG. 1 of the drawings, a characteristic positioning of the sections A, B and C places each of said sections on a substantial incline, there being sharp angular joinder at the top padding D between sections A and B while there is a gentle rounding at the opposite padding E, and there being sharp angular joinder at the bottom padding E between sections B and C while there is a gentle rounding at the opposite padding D.

While the joinder of the plurality of sections A, B and C is sharp and gentle as above described in the mattress constructed as hereinabove described, such is not the case with ordinary bedding. The difference in ordinary bedding occurs mainly at the said sharp angular joinder where no special provision is made to control bending.

Referring now to FIGS. 2, 3, 5 and 5a and to the head section A, a spring frame 10 is provided and which is adapted to function as a semi-rigid element giving permanent form to the section, as a resilient element giving de-pressible support for the section, and as a coupler element providing means of joinder to the next adjacent section. In order to perform the function of providing rigidity, the spring frame 10 involves upper and lower marginal rails, there being upper side rails 11 and 12 integrally joined by a transverse upper end rail 13, and there being lower side rails 14 and 15 integrally joined by transverse lower end rails 16 and 17. In accordance with the improved invention the forwardly disposed ends of the upper rails 11 and 12 are free and independent of each other. On the contrary, the rails 14—17 are rigidly joined beneath the free ends of rails 11 and 12 by the transverse rail, or spreader. The joinder of said rails are provided with right angle bends and each of which is gently rounded, as shown. It is significant that the forwardly disposed ends of the bottom side rails 14 and 15 remain free.

In order to perform the de-pressible support function, the spring frame 10 involves a set of coil springs 18, each of which is helically wound in the usual manner and of hour glass shape. In practice, for example, a bedding unit of the type under construction will be eighty inches in length, thirty-seven inches in breadth, and six and one-half inches in thickness. In this instance the head section A will be about thirty-six inches in length, in which case coil springs 18 having an end diameter of four inches are employed in tangential relation to each other, there being eight coil springs across the frame section and nine coils lengthwise of the frame section. The said frame section rails and said spring coils are suitably joined together as a unit, preferably by means of small diameter helical coils known in the art as "pig-tails" 60 and which are applied in the usual manner as best illustrated in FIGS. 3 and 4.

In order to perform the function as a coupler element, the said free ends of the upper side rails 11 and 12 extend beyond the foremost row of springs 18. In accordance

with the invention the forward extensions of the rails are straight and establish pivots with an axis of rotation displaced forwardly of the compressible support of section A. In practice, the frame elements are made of rod-like members that possess substantial resilience, and the terminal end of each extension is turned or bent into an eye for the reception of a similar eye of the next adjacent section B.

Referring now to FIGS. 2, 3, 4, 6 and 6a and to the center section B, the spring frame 20 is provided and which is adapted to function as a semi-rigid element giving permanent form to the section, as a resilient element giving compressible support for the section, and as a coupler element providing means of joinder to the next adjacent sections. In order to perform the function of providing 10 rigidity, the spring frame 20 involves upper and lower marginal rails, there being upper side rails 21 and 22 and lower side rails 24 and 25. It is significant that both the rearmost and foremost ends of the rails 21 and 22 are or remain free and independent, except for the coupling function to be described; and it is also significant that the foremost ends of the rails 24 and 25 are or remain free and independent. As is clearly illustrated, the foremost 15 ends of rails 21 and 22, and the rearmost ends of rails 24 and 25 are inwardly turned so as to eliminate sharp terminal ends at the mattress edge, and there is an intermediate transverse spreader 27 that is fastened to and extends between the rails 24 and 25 so as to maintain the breadth of section B. The said rails 21, 22, 24 and 25 are effective as continuations of said respective rails 11, 12, 14, and 15.

In order to perform the compressible support function, the spring frame 20 involves a set of coil springs 28 each of which is helically wound the same as springs 18. In this instance the center section B will be about seventeen inches in length, in which case there are eight coils across the frame section and four coils lengthwise thereof. The said frame section rails and said spring coils are suitably joined together as a unit, preferably by means of small diameter helical coils or "pig-tails" 60 and which are applied in the usual manner.

In order to perform the function as a coupler element, the rearmost free ends of the upper side rails 21 and 22 extend beyond the rearmost row of springs 28, and also the foremost free ends of the lower side rails 24 and 25 extend beyond the foremost row of springs 28. In accordance with the invention the said rearward and forward extensions of the rails are straight and establish pivots with axes of rotation displaced rearwardly and forwardly of the compressible support of section B, respectively. In practice, the rod-like frame elements are resilient and the terminal free end of each extension is turned or bent into an eye for the reception of a similar eye of the next adjacent section A and C.

Referring now to FIGS. 2, 4, 7 and 7a and to the foot section C, a spring frame 30 is provided and which is adapted to function as a semi-rigid element giving permanent form to the section, as a resilient element giving compressible support for the section, and as a coupler element providing means of joinder to the next adjacent section. In order to perform the function of providing rigidity, the spring frame 30 involves upper and lower marginal rails, there being upper side rails 31 and 32 integrally joined by transverse upper end rails 33 and 34, and there being lower side rails 35 and 36 integrally joined by transverse lower end rail 37. In accordance with the improved invention, the lower side rails 35 and 36 have rearwardly disposed ends that are free and independent of each other, and which are free except for the coupling function to be described. On the contrary, the rails 31-34 are rigidly joined above the free ends of rails 35 and 36 by the transverse rail, or spreader 34. As is clearly illustrated, said rails 31, 32, 35 and 36 are effective as continuations of said respective rails 21, 23, 24 and 25.

In order to perform the compressible support function,

the spring frame 30 involves a set of coil springs 38, each of which is helically wound the same as springs 18 and 28. In this instance the foot section C will be about twenty-seven inches in length, in which case there are eight coils across the frame section and seven coils lengthwise thereof. The said frame section rails and said spring coils are suitably joined together as a unit, preferably by means of small diameter helical coils or "pig-tails" 60 which are applied in the usual manner.

In order to perform the function as a coupler element, the rearmost free ends of the lower side rails 35 and 36 extend beyond the rearmost row of springs 38. The rearward extensions of the rails are straight and establish pivots with an axis of rotation displaced rearward of the compressible spring support of section C. In practice, the rod-like frame elements are resilient and the terminal free end of each extension is turned or bent into an eye for the reception of a similar eye of the next adjacent section B.

With the compressible and semi-rigid frame sections that are freely extended and have coupling means incorporated therein, as hereinabove described, an assembly thereof is made as shown in FIG. 2 (springs 18, 28 and 38 being omitted for clarity). The three otherwise independent sections are hingedly coupled by the interengaged eyes to articulate on the two transverse axes as indicated.

Referring now to the padding D (and E) and also the cover F: Generally, ordinary materials such as cotton batting, burlap, muslin and foam plastic are used in constructing the paddings D and E, and the cover F can be any high grade cotton ticking or the like. The padding D is provided to overlie the frame sections A, B and C and comprises a cushion and a heavy burlap layer is interposed between the frame sections A, B and C and the padding D, and the cover F is the usual envelope that encloses the bedding or mattress. It is preferred that the cover F be without buttons or ties as is clearly illustrated.

The mattress frame hereinabove described is especially suited to hospital bedding where substantial bending is required at the established bend lines between sections A, B and C. Said sections are well established as to size and the inner-springs of the mattress is capable of articulation at these bends, with freedom and without deleterious effects upon the mattress as a unit. The section A has a rigid rectangular underframe comprised of the rails 14-17, while the overframe thereof is comprised of the rails 11-13 and characterized by an open and unencumbered foremost end. Likewise, the rearmost end of the section B is open and unencumbered where it adjoins the section A, and at this point of joinder the adjacent rows of springs 18 and 28 are spaced by virtue of the extended free ends of the rails. Therefore, each pair of adjacent springs 18 and 28 is joined by an interconnecting helical tension spring 100 and to the end that there is continuity in the underlying spring support beneath the padding D. The section B has a rigid underframe comprised of rails 24-27, while its overframe is completely uninhibited with its two independent side rails. Further, the underframe of section B also reinforces the open rearmost end of the underframe of section C. The section C has a rigid rectangular overframe comprised of the rails 31-34. The frame, as a whole, is an inner-spring for a mattress that can articulate, and wherein each section thereof is especially suited for the support of that portion of a person which is to lie thereon. For such reasons, and not considering the uppermost supporting surface of the mattress, the section A is devoid of a forward rail, and the section B is devoid of both forward and rear rails, while the section C is complete with forward and rear rails. The springs of the three sections are separated so as not to interfere with each other, while the void between sections A and B is spanned by the interconnecting springs 100. The rail 34, section C, occurs beneath the knees of the person and presents a definite point of flexure. As a result, an inner-spring hospital mattress is provided

and which is adequately framed so as to be durable as well as comfortable.

Having described only a typical preferred form and application of my invention, I do not wish to be limited or restricted to the specific details herein set forth, but wish to reserve to myself any modifications or variations that may appear to those skilled in the art and fall within the scope of the following claims.

Having described my invention, I claim:

1. An inner-spring mattress comprising a plurality of normally horizontal and inclinably relatable sections and each with its own independent spring frame, each of said spring frames having side rails with transverse rows of vertically disposed spring coils, there being a common padding overlying the said sections and supported by said spring coils, and said adjacent spring frames being hingedly coupled by means of the side rails that are extended and pivotally joined end to end on a transverse axis at the plane of support beneath the padding.

2. An inner-spring mattress as set forth in claim 1 wherein the side rails are extended from the last row of spring coils of each section respectively, leaving a void between the sections, and wherein said void is spanned by support members connected between the complementary spring coils of said two sections.

3. An inner-spring mattress as set forth in claim 1 wherein one of the section frames has an underframe comprised of rectangularly related rails and has an overframe comprised of side rails joined by an end rail and open between said rails at the opposite end thereof, and wherein said one of the section frames is coupled to another section frame that has an underframe and has an overframe comprised of independent side rails, the rows of spring coils extending between the underframes and overframes respectively, and wherein the side rails of the overframes of both said sections are extended from the last row of spring coils of each section respectively and pivotally joined leaving a void between sections, and wherein said void is spanned by support members connected between the spring coils of said two sections.

4. An inner-spring mattress as set forth in claim 1 wherein one of the section frames has a rigid underframe comprised of rectangularly related rails and has an overframe comprised of side rails joined by an end rail and open between said rails at the opposite end thereof, and wherein said one of the section frames is coupled to another section frame that has a rigid underframe and has an overframe of independent side rails, the rows of spring coils extending between the underframes and overframes respectively, the side rails of the overframes of both said section frames being extended and hingedly coupled, leaving a void between sections, and wherein said void is spanned by support members connected between the spring coils of said two sections.

5. An inner-spring mattress as set forth in claim 1 wherein a first section frame has an underframe comprised

of rectangularly related rails and has an overframe comprised of side rails joined by an end rail and open between said rails at the opposite end thereof, wherein said first section frame is hingedly coupled to a second section frame that has an underframe comprised of rectangularly related rails and has an overframe comprised of independent side rails, wherein said second section frame is hingedly coupled to a third section frame that has an underframe and an overframe comprised of side rails joined by an end rail and open between said rails at the opposite end thereof and has a rigid overframe comprised of rectangularly related rails, and wherein said second section frame is hingedly coupled to the third section frame, the rows of spring coils extending between the underframes and overframes respectively, and wherein the side rails of the overframes of the hingedly coupled sections are extended from the last row of spring coils of each section respectively and pivotally joined leaving a void between the first and second sections, and wherein said void between the first and second sections is spanned by support members connected between the complementary spring coils of said two sections.

6. An inner-spring mattress as set forth in claim 1 wherein a first section frame has a rigid underframe comprised of rectangularly related rails and has an overframe comprised of side rails joined by an end rail and open between said rails at the opposite end thereof, wherein said first section frame is hingedly coupled to a second section frame that has a rigid underframe comprised of rectangularly related rails and has an overframe comprised of independent side rails, wherein said second section frame is hingedly coupled to a third section frame that has a substantially rigid underframe comprised of side rails joined by an end rail and open between said rails at the opposite end thereof and has a rigid overframe comprised of rectangularly related rails, and wherein said second section frame is hingedly coupled to the third section frame, the rows of spring coils extending between the underframes and overframes respectively, and wherein the side rails of the overframes of the hingedly coupled sections are extended from the last row of spring coils of each section respectively and pivotally joined leaving a void between the first and second sections, and wherein said void between the first and second sections is spanned by support members connected between the complementary spring coils of said two sections.
